UNITED STATES PATENT OFFICE.

RALPH J. WELLS, OF DAYTON, OHIO.

TRACK LINER AND METHOD OF APPLYING SAME.

Application filed June 27, 1927. Serial No. 201,640.

My invention relates to railway track construction, and particularly to means and methods of applying rail liners or cushion materials to absorb rail vibration and exclude 5 moisture.

The vibration of track rails due to passing traffic has a deteriorating effect upon the road bed tending to displace and disturb the fill material and open crevices adjacent to 10 the rails through which water is admitted. The water entering through such crevices not only softens the road bed material, but the freezing and thawing with its consequent expansion during the winter season causes 15 crumbling and hastens the deterioration of the road bed. This destructive action incident to rail vibration is particularly noticeable in paved track and where the track had been concreted. The vibration of the rails 20 causes disintegration of the concrete and paving material and induces cracks and breakage of such road bed material in addition to the crevices opened contiguous to the rails. Attempts have heretofore been made to over- 25 come this difficulty by providing preformed rail liners of asphalt, or the like, molded into strips or bars which conform to the contour of the track rail. To be effective, however, such material must be sufficiently "sticky" to 30 adhere to the sides of the track rail and also to the contiguous portion of the road bed fill material. Such molded liners sufficiently soft and "sticky" to serve the purpose well are inconvenient to handle and stick to each 35 other prior to introduction into the track structure. To overcome this difficulty in handling, it is customary to coat the surface of such liners with marble dust or fine sand, or the like. The use of such surface mate- 40 rial to enable handling, subsequently prevents a perfect union or adherence of the liner to the track rails and the road bed mate- 45 rial and thus defeats the purpose. Moreover, such preformed liners require extreme care in their application. The workmen do not always place the liners carefully in close con- 50 tact with the rails and sometimes the liners bend out of shape thereby leaving air pockets. Another difficulty of such pre-formed 55 liners is encountered in cold weather when such material becomes hard and brittle and subject to excessive breakage during instal- 60 lation.

The present invention is intended to over- 55 come these difficulties of installation by form-

ing the liner in situ subsequent to the completion of the track structure and the paving or concreting of the road bed. To this end forms are inserted adjacent to the track rail which confine the road bed material, whether 60 it be earth fill, concrete or brick paving, leaving in juxtaposition to the web of the track rail and beneath the head flange thereof a longitudinal chamber having a constricted access slot adjacent to the flange of the rail. 65 When the concrete fill has sufficiently set or the paving has been completed over the road bed, such spacing forms are withdrawn and the space or chamber intermediate the rail and road bed material is filled with a plastic 70 or semi-fluid cushion and sealing material. This material is preferably an asphalt base containing a filler of other materials. This resilient cushion material is poured into the chamber through the access slot and allowed 75 to set or harden therein. It adheres closely and uniformly to the track rail and the adjacent face of the pavement or the fill of concrete or other material. By thus mold- 80 ing the liner in situ the difficulties of han- 85 dling are obviated and a perfect union of the material with the rail and adjacent face of the road bed or fill material is established.

The object of the invention is to simplify 85 the form as well as the means and mode of applying rail liners to railway construction, whereby they will not only be cheapened but will be more efficient, capable of being easily and quickly applied and adaptable to varying conditions and irregularities of surfaces 90 and affording insurance against the formation of air pockets.

A further object of the invention is to pro- 95 vide an improved form of track seal which will exclude moisture.

A further object of the invention is to pro- 100 vide an improved form of cushion or resilient bond between the track rail and the road bed filling material which will dampen vibration and protect the road bed material and paving 105 against deterioration.

A further object of the invention is to pro- 105 vide an improved form for confining the road bed material to produce intermediate the road bed fill and rail a chamber having a 110 constricted orifice to receive a body of resil- 110 ent sealing material.

A further object of the invention is to pro- 110 vide a method of applying in situ a body of resilient sealing material to track rails.

With the above primary and other incidental objects in view as will more fully appear in the specification, the invention consists of the features of construction, the parts and combinations thereof, and the mode of operation, or their equivalents, as hereinafter described and set forth in the claims.

Referring to the accompanying drawings, Fig. 1 is a transverse sectional view of a portion of a railway track construction to which the present invention has been applied, illustrating therein successive stages of the process or method. Fig. 2 is a detail perspective view showing a form member positioned beside a track rail preparatory to filling or paving the road bed. Fig. 3 is a detail view illustrating a modification of the form member. Fig. 4 is a detail perspective view of a further modification of the form member. Fig. 5 illustrates a modification of the method or process wherein the cushion material in plastic form is applied to the rails prior to filling the track bed.

Like parts are indicated by similar characters of reference throughout the several views.

In the accompanying drawings 1—1 represent the track rails mounted upon any suitable cross tie. In the present construction the rails 1 are shown mounted upon the sleeper block 2—2 interconnected by transverse angle bars 3. The sleeper blocks 2 are preferably superposed upon a bed or stratum of asphalt or other cushion material. Such tie construction forms no part of the present invention but is fully and clearly described and claimed in prior patents. Ordinary wood cross ties may be employed if desired. The cross ties of whatever type are embedded in a fill of concrete or gravel ballast as is usual.

Before completing the road bed fill 4 and the surface pavement, if the latter is to be laid, forms are set on opposite sides of the rails 1—1 to limit the approach of the filling material and pavement toward the rails. Such form side may be an ordinary plank as shown at 5 in Fig. 1, which is set on edge in a vertical plane beside the rail 1 with the top margin of the plank bearing against the side of the rail flange or head.

This form member or plank 5 affords beneath the rail flange or head and between the plank 5 and the web of the rail 1, a longitudinal chamber 6. After the fill has been completed intermediate the rails 1, at opposite sides thereof, and the surface pavement laid, the form plank 5 is withdrawn. This leaves beside the flange or head of the rail 1 a substantially parallel slot, (previously occupied by the margin of the plank) communicating with the chamber 6. Resilient sealing material, preferably asphalt intermixed with a suitable filler material, is poured through the slot into the chamber 6 while in a molten or semi-fluid condition. The liquid asphalt or

other resilient sealing material completely fills the chamber or passage 6 and conforms closely to the surfaces of the rail 1 and the body 4 of filling material. Not only does the material poured within the chamber 6 completely fill such chamber, but it adheres to the walls of the chamber forming perfect union therewith to exclude water. By pouring the material into the chamber or passage 6 while in a soft or fluid condition such material will flow about and conform to the bolt heads and nuts and to the spike heads as well as other irregularities of surface, and the liner 7 thus formed becomes a continuous strip or body, whereas preformed liner strips 80 must necessarily be installed in sections.

In lieu of an ordinary plank 5 used as a form member for confining the body of filler material 4, such form preferably consists of a section of sheet metal having its margins 85 bent laterally to form substantially parallel flanges 9 and 10. The wider flange 10 at the bottom of the sheet metal form 8 rests upon the rail base and bears against the web of the rail to hold the form side 8 in spaced relation. At the same time the narrow marginal flange 10 at the top of the form member 8 bears against the side of the rail head or flange to hold the form side 8 sufficiently spaced therefrom to afford the entrance or 95 communicating slot through which the resilient sealing material may be deposited to form the liner 7. Whether the simple form of a plank 5 or the flanged sheet metal form 8 is employed, U shaped yokes 11 are found convenient for holding the form side members in their adjusted positions relative to the rail 1 while the fill and paving is being completed on opposite sides of the rail. Such yokes 11 are adapted to simultaneously hold form 105 members on opposite sides of the rail 1. Upon completion of the fill 4 of road bed material, or the paving of the road bed as the case may be, the form members 8 are preferably withdrawn. The shape of the form member is such that upon being elevated sufficiently to bring the lower lateral flange 10 beneath the head of the rail, the form may be turned laterally as shown by dotted lines to enable the removal of the lower flanged portion 10 through the slot intermediate the rail and the fill of road bed material. If necessary, the flanged portion 10 may be bent or flexed outwardly by pulling upon the form 8 during its removal to enable the angle of the 110 form to pass through the slot. In Fig. 3 there is shown a modification where in lieu of the lower lateral integral flange 10, the form side 8 is provided with pivoted spacer arms 115 which rest upon the base of the rail and abut against the web portion thereof to hold the lower part of the form 8 in its adjusted position. Upon withdrawing the form 8 the spacing fingers 12 will fold downwardly about their pivotal connection 13 to pass 130

easily through the slot intermediate the fill of road bed material and the head or flange of the rail 1 through the slot formed by the lateral flange 9 of the form.

5 If desired the sheet metal forms may be permanently embedded and left in the road bed. In such case the top flange 9 would be cut away at intervals as at 9' in Fig. 4 to enable access to the chamber 6 for deposit of the 10 cushion material.

While the preferable method is to pour the resilient sealing material into the chamber or passage 6 while in a semi-fluid or molten state, an alternative method is to apply the 15 material in a plastic form directly to the side of the rail, filling the recess between the head or flange of the rail and the base thereof prior to depositing the fill of road bed material. Such modified method is illustrated in 20 Fig. 5. Instead of pre-forming the liner 7 in a molded bar the material in a soft or plastic condition is applied to the rail side with a trowel or is tamped or rammed into place and into close conformity with the rail as 25 shown at 14 prior to the deposit of the fill 4 of road bed material. The latter, whether of earth or of concrete, when deposited will conform to the side of the liner 7 so that the 30 liner of resilient sealing material will form a close contact therewith.

In lieu of applying the material in a plastic form as shown at 14 in Fig. 5, it may be poured or molded in situ in quite the same manner as that heretofore described by pouring the semi-liquid or molten material between the rail and the form member 8 as 35 shown at 16 in Fig. 5. In this instance the form member 8 is not provided with the bottom inturned flange 10 but is formed with an 40 offset or rabbet 15 resting against the base of the rail to insure proper spacing of the sheet metal form member 8. The top flange 9 of such form member is cut away or removed at spaced intervals as at 9' to enable 45 the deposit of the sealing and cushion material within the chamber formed intermediate the sheet metal form side 8 and the web of the rail.

After the material has set the form may be 50 stripped from the deposited cushion material 16 and the concrete or other roadbed fill material subsequently deposited in contact with the deposit of cushion material. In this case the grouting or concrete fill or paving, as the 55 case may be, will conform closely to the deposit of cushion or filling material. However, the method of depositing the concrete or road bed material first and subsequently pouring the cushion or sealing material while 60 in a semi-fluid condition is to be preferred since it insures uniform adhesion of the cushion material to the road bed fill or concrete as well as to the rail and affords a continuous resilient bond.

65 To facilitate the loosening or stripping of

the form members from the concrete or road bed deposit a small clearance is preferably left between the form and the side of the rail head. At the right in Fig. 1, wedges 17 have been shown interposed between the form 70 plank 5 and the rail. By removal of the wedges the plank 5 is allowed sufficient movement toward the rail to facilitate its separation from the concrete deposit or paving preparatory to removal. In lieu of the wedges 75 17 the retaining yokes 11 (Fig. 2) may be provided with dependent fingers 18 projecting intermediate the form member and the rail head to insure the relative spacing of the form sides and provide a clearance space sufficient 80 to facilitate the stripping or loosening of the sheet metal form.

While the cushion or sealing material has been described as asphalt or an asphalt base with suitable filler, it is to be understood that 85 it is not limited to this particular material. While a material of bituminous character is preferred, not only for its convenience of application but for its resilience and non-deteriorating characteristics, it is to be understood 90 that other materials of non-bituminous character but capable of assuming a plastic or semi-liquid character which facilitates its deposit through the restricted slot into the chamber beside the rail, may be employed in 95 lieu of a bituminous material.

From the above description it will be apparent that there is thus provided a construction of the character described, possessing the particular features of advantage before enumerated as desirable but which obviously is susceptible of modification in its form, proportions, and arrangement of parts, without departing from the principle involved or sacrificing any of its advantages.

While in order to comply with the statute the invention is described in language more or less specific as to structural features, it is to be understood that the invention is not limited to the specific details shown, but that the means and construction herein disclosed comprise the preferred form of several modes of putting the invention into effect, and the invention is therefore claimed in any of its forms or modifications within the legitimate 110 and valid scope of the appended claims.

Having thus described my invention, I claim:

1. In a railway track construction, the combination with a rail including a head portion, a web and a base, of a body of road bed material terminating in a substantially vertical plane contiguous to the head of the rail, and a body of resilient material molded in situ beneath the head of the rail and against the web thereof and filling the space between the body of road bed material and the rail web.

2. In a railway track construction, the combination with a railway rail, including a head 120

125

130

130

portion, a web and the base, of a body of concrete road bed material molded in situ in spaced relation with the web of the rail and approaching into proximate relation with the

5 head thereof, and a body of resilient material extending substantially from the base to the head of the rail and molded in situ into conformity with the rail web and filling the space intermediate the web of the rail and the concrete body.

10 3. The herein described method of railway track construction including positioning a form member in spaced relation with a railway rail to form a linear crevice adjacent to the rail flange communicating with an enlarged chamber beneath the rail head and contiguous to the web of the rail, depositing road bed material beside said form and filling the chamber with plastic material deposited 15 through said crevice.

15 4. The herein described method of railway track construction including positioning a removable form member adjacent to a track rail to form a chamber contiguous to and

20 parallel to the rail, depositing road bed material at one side of said form, removing the form and filling the chamber with plastic material.

25 5. The herein described method of railway track construction including positioning a removable form member adjacent to a track rail, depositing road paving material at one side of the form which is confined thereby in spaced relation with the rail to afford a contiguous parallel chamber having a constricted entrance slot adjacent.

30 6. In a construction of the character described, the combination with a railway rail of a removable sheet metal form member having laterally flanged margins, one flange of which engages the side of the rail head and the other flange of which engages the rail adjacent to its base portion, said form serving to confine the adjacent road fill material in spaced relation with the rail to afford an intermediate chamber having a constricted entrance slot to receive a body of sealing material deposited in said chamber through said slot subsequent to the removal of the form.

35 50 7. In a construction of the character described, the combination with a railway rail of a form member serving to confine adjacent road fill material in spaced relation with the rail to form an intermediate chamber, means for spacing the form side from the rail head to afford an entrance opening to said chamber, to receive a body of sealing material deposited in said chamber through said entrance opening subsequent to the deposit of the road fill material.

60 8. In a construction of the character described, the combination with a track rail, a body of concrete deposited adjacent thereto, means for forming a chamber intermediate the web of the rail and the body of concrete,

said chamber having an access opening thereto and a body of resilient sealing material deposited in said chamber through said access opening.

65 9. In a construction of the character described, the combination with a track rail, of a body of resilient sealing material formed in situ against said rail and completely filling the lateral recess of the rail from its base to its head and extending from the web of the rail 70 to a substantially vertical plane approximately flush with the side of the rail head, and a body of concrete molded in situ and separated from the rail by said intermediate body of resilient sealing material.

75 10. In a track construction of the character described, the combination with a track rail including head, base and web portions, of a body of plastic material formed in situ in filling the lateral channel of the rail between the 80 base and head and conforming to the web of the track rail and a body of initially plastic road fill material separated from the rail by said body of plastic material.

85 11. In a construction of the character described, the combination with a track rail of a body of resilient material molded in situ beneath the head of the rail and contiguous to the web thereof and a body of concrete road bed material molded in situ and contacting 90 the resilient body, the first deposited body forming a wall for confining the second deposited body.

95 12. The combination with a track rail of a body of resilient material molded in situ beside the rail, filling the channel beneath the rail head and terminating in a substantially vertical plane therebeyond, and a body of road bed material abutting thereon.

100 13. The combination with a track rail of a body of road bed material terminating in a substantially vertical plane exteriorly of the head of the rail, and a deposit of resilient material molded in situ beneath the rail head and beside the web of the rail completely filling such space and abutting upon the road bed material.

105 14. The combination with a railway rail of a form member located beside the rail and extending from the base to the head thereof 115 forming intermediate the member and the rail a chamber to receive a deposit of resilient material and exteriorly of the member a space to receive a deposit of road bed material.

110 15. The combination with a railway rail of a rail filler of resilient material molded in situ beneath the head of the rail and against the web and completely filling the recess between the rail base and head thereof and extending to a substantially vertical plane laterally spaced from the side of the rail head.

115 16. In combination, a track rail comprising a head, a web and a base, and a paving structure adjacent thereto and comprising 120

substantially non-elastic material terminating at said base with a cavity between the paving material and web extending from the head to the base and a filler of plastic material mold-
5 ed in situ filling said cavity and supported by said substantially non-elastic material against extrusion beyond said base.

17. The herein described method, consisting in positioning a form member beside a
10 railway rail in a substantially vertical position extending from the base to the head of the rail, thereby forming at one side a space to receive plastic material adjacent to the web of the rail and beneath the head thereof and
15 forming at the opposite side of the form member a space to receive road bed material, filling one of said spaces with the corresponding afore-mentioned material, removing the form

member and subsequently filling the other space with the other mentioned material. 20

18. The herein described method, consisting in positioning a form member beside a railway rail in a substantially vertical position extending from the base to the head of the rail, thereby forming at one side a space 25 to receive plastic material adjacent to the web of the rail and beneath the head thereof and forming at the opposite side of the form member a space to receive road bed material, filling one of said spaces with the corresponding 30 aforementioned material and filling the other space with the other mentioned material.

In testimony whereof, I have hereunto set my hand this 15th day of June, A. D. 1927.

RALPH J. WELLS.
